ARRANGEMENT FOR PROTECTING THE ELECTRODES IN DEMOUNTABLE HIGH VACUUM TUBES

Max Graf, Baden, Switzerland, assignor to "Patelhold" Patentverwertungs & Elektro-Holding A.-G., Glarus, Switzerland

Application February 4, 1943, Serial No. 474,754
In Switzerland December 10, 1941

4 Claims. (Cl. 315—107)

1

It is known that in high vacuum tubes the vacuum can deteriorate and this may cause ignitions with the result that a cathode spot forms on the cathode or on a grid which may result in the electrodes being destroyed. In order to avoid this risk of destruction it has been usual to employ excess-current relays on the assumption that such ignitions are identical with short-circuits and therefore result in high excess currents. This is, however, not correct. Under certain circumstances, for instance when the anode voltage is reduced or when there is a circuit with large external resistance, the current does not increase unduly when an ignition occurs, although a cathode spot is formed. The electrodes are endangered, however, because the excess-current protection does not operate.

According to the present invention therefore the condition of the vacuum in the tube and not the magnitude of the anode current is taken as the criterion for the operation of the protective device.

Demountable tubes have already been equipped with high vacuum measuring devices which enable the state of the vacuum to be determined. The invention goes a step further, however, because when there is a poor vacuum in the tube the anode circuit is automatically interrupted.

A constructional example of the invention is illustrated diagrammatically in the accompanying drawing. The problem is to protect the electrodes of the demountable transmitting tube *a* against the effects of a poor vacuum. The tube *a* is directly connected to a high vacuum pump *b*, in this case a molecular pump, which is driven by the motor *c*. In the suction conduit between the pump *b* and the tube *a* an ionization manometer *d* is fitted in a vacuum tight manner, this being shown in section and consisting mainly of a glow discharge tube with its discharge gap located in the field of a permanent magnet. The electrodes of this tube *d* are connected to a constant alternating voltage *e* of about 2000 volts and the glow current varies with the vacuum. It can be read off the measuring instrument *f* and flows through the potentiometer resistance *g*.

The voltage drop produced by the glow current and depending on the vacuum is picked up at *h* and passed as a negative grid voltage to the grid of the amplifying tube *i*. The poorer the vacuum the higher the grid voltage and the smaller the anode current will be, until this latter becomes so small that the electromagnetic relay *m* which is supplied from the network *k* drops out. This relay is located in the remote control circuit (not

2

shown in full in the drawing) of the anode circuit of the demountable tube *a* which is to be protected and causes its main switch to open.

The same device can also be employed to switch in the demountable tube automatically when the vacuum improves. Due to the difference between the pick-up current and the drop-out current of the relay it is possible to arrange for the voltage of the main tube to be switched in again only when the vacuum is considerably higher than it is at the instant when the relay responds.

If the vacuum is very poor the hot cathode may even burn out. In order to prevent this a second relay *n* can be provided whose excitation voltage is tapped from a smaller section *o* of the resistance *g* over the tube *p*. When the pressure in tube *a* rises above a certain value which is higher than that at which the first relay *m* responds, relay *n* also drops out and interrupts with an adjustable time lag the heating current circuit of the cathode. This delay is expedient so that when a sudden deterioration of the vacuum occurs, such as may occur for instance when a demountable tube is being evacuated, the heating current is not unnecessarily interrupted. The same ionisation manometer *d*, which serves both for measuring the high vacuum and for interrupting the anode voltage when a slight deterioration of the vacuum occurs, can be used to control this second and less sensitive relay. The relays *m* and *n* preferably have back contacts for closing circuits of signal or alarm devices, as indicated by the legend "Alarm circuits," when the relays drop out to open the energizing circuits of the tube *a*.

I claim:

1. In a tube assembly in which the vacuum in the tube is to be maintained, the combination with a tube having anode and heater circuits associated therewith, and a vacuum pump for evacuating the tube, of relays having contacts for completing said anode and heater circuits, and circuit means responsive to the vacuum within said tube for selectively controlling said relays to open said anode circuit upon an increase of the tube pressure to one value and to open the heater circuit upon an increase of the tube pressure to a higher value.

2. In a tube assembly, the invention as recited in claim 1, wherein said relays are electromagnetic relays, and said circuit means includes a vacuum tube relay for energizing each of said electromagnetic relays.

3. In a tube assembly, the invention as recited in claim 1, wherein said circuit means comprises

a control circuit including a source of current in series with a tapped resistance and with a circuit element subject to the vacuum within said tube and having an effective resistance that varies with the vacuum condition, and energizing circuits for the respective relays connected across different magnitude portions of said tapped resistance.

4. In a tube assembly in which the vacuum in the tube is to be maintained, the combination with a high vacuum transmitting tube having an anode circuit associated therewith and a vacuum pump for evacuating said tube during operation thereof, of means responsive to a dangerous pressure rise within the tube for opening said anode circuit, said means comprising an ionization manometer subject to pressure within said tube, said manometer being a glow discharge tube having spaced electrodes and a permanent magnet es-

tablishing a magnetic field in the discharge gap between said spaced electrodes, a resistance connected in series with said manometer and therewith across a current source of a magnitude establishing a glow current across the discharge gap, an amplifying tube including a grid and an anode cooperating with a cathode, circuit elements connecting said grid and cathode to spaced points on said resistance in such sense that a negative bias is impressed upon the grid by current through said resistance, whereby the anode current of said amplifier tube decreases with an increase in the pressure within said transmitter tube, and a relay in the anode circuit of the amplifier tube having contacts for completing said anode circuit of the transmitting tube during energization of said relay.

MAX GRAF.
